UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

1,419,991.

Specification of Letters Patent. Patented June 20, 1922.

Application filed May 4, 1920. Serial No. 378,751.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to collating devices, 10 or devices for effecting proper relative positioning of a plurality of work-sheets, and is in the nature of an improvement on my co-pending application, Serial No. 375,676, filed April 22, 1920.

15 The mechanism disclosed in said co-pending application is designed for work in which typewritten impressions of names and addresses, or other entries, are made close together on a record-sheet, and at greater distances apart on a form or bill-strip, one address or entry being placed on each bill or form. The said mechanism is so arranged 20 that, in order to obtain the desired result, the record-sheet and the bill-strip are introduced with the record-sheet on the outside, thus necessitating the use of a record-sheet of lighter weight than usual, in order to obtain a suitable carbon impression on the bill, which is to be forwarded to the customer.

25 Also in that mechanism, the record-sheet, during the advance of the bill-strip relative thereto, is held against advance movement by means located adjacent the front paper table, by which the bill-strip is received

30 from the platen, and the position of the bill-strip for different bills is determined by means of a spring-pressed register pin adapted to be projected through perforations in the bill-strip into a perforation in the front paper table, when one of said perforations 35 in the bill-strip is brought into register with that in the paper table.

According to the present invention, the record-sheet is placed on the inside, that is, 40 next to the platen, and receives the carbon impressions while the ribbon impressions are received by the various bills of the bill-strip. With this arrangement, record-sheets of any desired weight may be used, and the bills 45 sent to the customers will be ribbon impressions, and will, therefore, present a better appearance.

In the embodiment of the invention herein disclosed, the record-sheet may be held

against advance movement, while the bill-strip is being advanced relatively thereto, by suitable devices which are adapted to press the record-sheet against the rear paper table, and the initial position of each of the bills may be determined automatically by a spring-pressed pin urged to pass through a perforation in the paper table, to co-operate with the bill-strip on the opposite side, suitable means being provided to engage the bill-strip on its outer side, and enable the bill-strip to restrain the spring-pressed pin until the perforation in the bill-strip is advanced to a position to receive the pin.

Provision may also be made of a handle, and of suitable connections to enable the record-sheet controlling devices associated with the rear paper table, and the spring-pressed pin associated with the forward paper table, to be rendered effective or ineffective concomitantly.

When the record-sheet is held at the rear paper table, and the bill-strip drawn forward, the frictional engagement between the bill-strip and the record-sheet will tend to draw the latter forward, and maintain it in proper position on the platen, whereas, in case the record-sheet is held by devices adjacent the front paper table, the bill-strip will tend to draw the record-sheet forward, and cause a bulge between the platen and the holding devices.

Other features and advantages will hereinafter appear.

In the accompanying drawings,

Figure 1 is a perspective view of a platen frame of an Underwood standard typewriting machine, with my invention applied thereto, parts being broken away to show the underlying structure.

Figure 2 is a front view of the structure shown in Figure 1.

Figure 3 is a side view, partly in section, showing the parts in normal position, with the record-sheet and form-strip positioned by means of the respective leading-edge gages.

Figure 4 is a detail of the parts shown in Figure 3, the spring-pressed pin being restrained by means of the bill-strip.

Figure 5 is a view similar to Figure 3, but with the parts shown in position to clamp the record-sheet against the rear paper table, and with the bill-strip advanced sufficiently

to bring a perforation therein into register with the perforation in the paper table, thereby permitting the register pin to project therethrough.

- 5 The revoluble platen 1 is supported by means of an axle 2 in end walls 3 of a platen frame 4 of the usual Underwood type, and may be turned either by finger-wheels 5, or by means of a line-space lever 6 acting 10 through a slide 7 and a pawl 7^a to actuate a ratchet wheel 8 fixed on said axle 2. The line-space mechanism may be substantially the same as that disclosed in the patent to Frederick A. Hart, No. 1,281,160, dated 15 October 8, 1918.

In use a record sheet 9 and a bill strip 10, consisting of a series of detachable bills of the same length, are passed over a rear paper-table 11 and between the platen and 20 rear feed-rolls 12 and front feed-rolls 13, which may be released during such insertion, the record sheet being placed next to the platen. The leading edge of the record sheet may be gaged by means of arms 14 and 25 15 having aligned edges with which the leading edge of the record sheet may be brought into coincidence, and the position of the record sheet transversely of the machine may be determined by a side edge gage 16 30 adjustably secured to one of said arms, preferably 15, by means of a screw 17 extending through a slot in said arm 15.

The bill strip 10 may be led from the platen upon a paper-table 18, and its leading edge brought into coincidence with a leading-edge gage 19 preferably formed in the paper-table itself, the bill strip being positioned transversely of the machine by means of a side edge gage 20. Said paper-table 18 may be supported by means of a bar 21 to which it may be secured by means of screws 22, the bar 21 being supported by brackets 23 provided with flanges or plates 24, which may be connected with the platen 40 frame by means of screws 25. The release of the feed-rolls may be effected by means of a feed-roll-release lever 26 acting through mechanism similar to that disclosed in said patent to Hart, No. 1,281,160.

50 The feed-rolls 12 and 13 may be restored to normal position by means of the feed-roll-release lever 26, and a name and address or other entry then printed by means of type-bars 27 through a ribbon, not shown, on the bill strip 10, and a carbon copy made on the record sheet 9 by means of an interleaved carbon 28. The work-sheets may be advanced after the writing of each line by means of line-space lever 6, the last actuation 55 of the latter carrying the record sheet into position to receive the first line of a new name or address. It will then be necessary to advance the form-strip until the next bill is properly positioned to receive a new 60 name and address.

In preparation for such movement of the bill strip, a handle 29 is drawn forward from the position shown in Figure 3 to the position shown in Figure 5, thereby permitting, at each side of the machine, a presser member 30, carried by lever 31, to be pressed against the rear table 11 by means of a spring 32, which tends to turn said lever 31 about its pivot 33, and releasing a pin 34 to the control of a spring 35, which urges the 70 same in a direction to enter perforations 36 and 37 in the paper-table 18 and in a finger or arm 38 projecting from the side edge gage 20, so as to permit the margin of the bill strip to be inserted between said finger and 75 said paper-table 18. Upon reference to Figures 4 and 5, it will be evident that the pin 34 when released will be restrained by the bill strip as indicated in Figure 4, and that when the bill strip is advanced to the proper 80 extent as determined by a perforation therein, the pin 34 will be permitted to advance to the position indicated in Figure 5.

The feed-rolls 12 and 13 may then be cast off by means of the lever 26, and the bill 90 strip 10 grasped by the operative and drawn forward until a perforation in the next form or bill is brought into register with perforations 36 and 37, thereby permitting the projection of pin 34 through the perforation in 95 said form. It should be understood that during such forward movement of the bill strip, the record sheet is gripped between the presser members 30 and the rear paper-table 11 and held against advance movement. The handle 29 may then be returned to the position shown in Figure 3, thereby withdrawing presser members 30 from the rear paper-table 11 by means of links 39, one of which connects said handle 29 with 100 the lever 31, and retracting said pin 34 to the rear of said paper-table 18 by means of an arm 40 fixed on a rock-shaft 41 to which said handle 29 is also fixed, and having a forked end embracing said pin 34, which is 105 provided with a head 42 to enable such retraction by means of arm 40. It will be seen that the link 39 at the right (Figure 2), is connected with rock-shaft 41 by means of an arm 41^a fixed on the latter. The work-sheets 110 will be positioned for the printing of another name and address which may be effected after restoration of feed-rolls 12 and 13 to effective position. The operation just described may be repeated as many times as 115 there are forms remaining in the bill strip.

120 Preferably the pin 34 is supported and guided by a cylindrical casing 43, secured to the back of the paper-table 18, and provided with an opening in its head in which the pin 125 has a sliding fit. The bore of this cylinder is of sufficient size to receive a collar 44 on pin 34, between which, and the head of the casing the spring 35 is supported on the pin.

130 It will be seen that springs 32 associated

with levers 31 and spring 35 associated with pin 34 tend to throw the handle 29 forward from the position shown in Figure 3 in which it is retained during the writing of a name and address. For the purpose of retaining the handle in its rearward position, provision may be made of a leaf spring 45 fixed on said handle at one end, and provided at its other end with a pin 46 having a rounded head adapted to operatively engage in a depression 47 in the adjacent bracket 23, the relation between the head of the pin 46 and the depression 47 being such that the pin will ride out of the depression when the handle 29 is drawn forward.

It should be understood that presser members 30 and pin 34 may be used in connection with the original positioning of the record-sheet and bill-strip. After casting off feed-rolls 12 and 13, the record-sheet 9 and the bill-strip 10 with the carbon-sheet therebetween are introduced between the platen and the feed-rolls, and the record-sheet and carbon-sheet passed beneath the front paper-table and a rock-shaft 41, the leading edge of the record-sheet being gaged by means of arms 14 and 15. Handle 29 may then be drawn forward and the record-sheet gripped between the presser members 30 and the rear paper-table 11, the bill-strip being then drawn forward until its leading edge engages with the pin 34, which projects through the forward paper-table 18, so that when engaged by the leading edge of the bill-strip, the position of said bill-strip will be substantially the same as when positioned by the leading-edge gage 19. Obviously, the leading-edge gage 19 may be dispensed with and the pin 34 used for this purpose.

It will be seen that the arrangement of the parts herein disclosed not only enables a ribbon-impression to be made on the bill-strip, but also, in view of the arrangement of the gripping devices to co-operate with the rear paper-table, and of the positioning of the side edge gage 16, so as to project downwardly from the supporting arms 15, the greater part of the mechanism is included between the end walls of the platen-frame whereby a very compact arrangement of the parts is obtained.

Although the strip 10 has usually been referred to herein as a bill-strip and the entries as names and addresses, it is obvious that the strip may be composed of other forms, and the entries may be other than names and addresses.

Variations may be resorted to within the scope of the invention, and portions of the improvements may be used without others.

Having thus described my invention, I claim:

1. In a typewriting machine, in combination, a revolute platen, a rear paper-table

over which superposed work-sheets may be fed to the platen, means to receive said work-sheets from the delivery side of the platen, a device to co-operate with the rear paper-table to hold one of said work-sheets near one of its side edges, so that a second work-sheet with its corresponding side edge positioned to clear said device may be drawn forward with reference to the work-sheet so held, and means for automatically arresting the second work-sheet when it has been advanced to a predetermined position.

2. In a typewriting machine, in combination, a revolute platen, a rear paper-table over which superposed work-sheets may be fed to the platen, means to receive said work-sheets from the delivery side of the platen, a member to co-operate with said rear paper-table to hold one of said sheets, a finger-piece, means whereby said member may be withdrawn from effective position by means of said finger-piece, means whereby said finger-piece may be latched in position with said member in withdrawn position, and means for automatically arresting another work-sheet when advanced to a predetermined position.

3. In a typewriting machine, in combination, a revolute platen, means to feed a record sheet and a second sheet to the platen, the record sheet lying next the platen, means whereby the leading edge of the record sheet may be gaged, a paper-table to receive said second sheet, said paper-table having a perforation adapted to register with perforations in said second sheet, a spring-pressed pin positioned to be projected through the perforation in the paper-table, and a member having a perforation in register with that in the paper-table, said member serving to maintain said second sheet in proximity to said paper-table, so that said second sheet may prevent said pin from entering the perforation in said member until said second sheet is advanced to bring a perforation therein in registration with the perforation in said member.

4. In a typewriting machine, in combination, a revolute platen, a rear paper-table for delivering a record sheet and a second sheet to the platen, a second paper-table to receive said second sheet from the platen, a device associated with said rear paper-table to hold said record sheet against advance movement, and means to prevent further movement of said second sheet when the latter has been advanced to a position determined by the configuration of said second sheet.

5. In a typewriting machine, in combination, a revolute platen, a rear paper-table for delivering a record sheet and a second sheet to the platen, a second paper-table to receive said second sheet from the platen, a device associated with said rear paper-table

to hold said record sheet against advance movement, means to prevent further movement of said second sheet when the latter has been advanced to a position determined by the configuration of said second sheet, and means for concomitantly rendering said holding device and said preventing means ineffective.

6. In a typewriting machine, in combination, a paper-table, a side edge gage associated with said table, a member adjacent said gage and overhanging said paper-table, but spaced therefrom so as to permit the insertion of a work-sheet therebetween, said

15 paper-table and said member having perforations in register with each other, a pin adapted to project through said perforations and enter perforations in the work-sheet when the latter is properly positioned, spring

20 means yieldably urging said pin to projecting position, but permitting said pin to be restrained by said work-sheet, and means to retract said pin below the level of the paper-table to permit a sheet to be inserted 25 between said paper-table and said member.

7. In a typewriting machine, in combination, a revolute platen, a rear paper-table for delivering two superposed work-sheets to the platen, a device associated with said rear 30 paper-table to hold one of said sheets against movement when desired, means at the delivery side of the platen to engage in perforations made in the second sheet at intervals, and means to render said device and 35 engaging means effective and ineffective concomitantly.

8. In a typewriting machine, a paper-table having a perforation, a pin yieldingly urged to project therethrough to the paper-guiding side of said table, and means to prevent separation of a work-sheet from said paper-table by said yieldingly urged pin, whereby said pin will be maintained in depressed position until said sheet is advanced

40 to a position with a perforation therein over the perforation in said table, whereupon said pin will be projected through the sheet to properly position the same.

9. In a work-sheet-positioning device for 50 typewriting machines, in combination, a paper-table, a side edge gage on said paper-table, an arm extending from said gage over said paper-table and spaced therefrom sufficiently to permit insertion of the edge of a

55 work-sheet, said paper-table and said arm having perforations in register, a pin supported behind said table in alignment with said perforations, and means to yieldingly urge said pin through said perforations,

60 whereby the work-sheet passed between said arm and said paper-table may prevent the advance of said pin until the advance of the work-sheet causes a perforation therein to be brought into position to permit advance 65 of said pin.

10. In a typewriting machine, in combination, a revolute platen, a paper-table for guiding work-sheets to the platen, a second paper-table to receive work-sheets from the platen, a device associated with the first- 70 mentioned paper-table to hold a work-sheet against advance movement, a device associated with the second paper-table to co-operate with a work-sheet of special configuration to prevent further advance thereof after 75 the latter has been advanced to a predetermined extent, and means whereby both of said devices may be made effective or ineffective.

11. In a typewriting machine, in combination, a revolute platen, a paper-table for guiding work-sheets to the platen, a second paper-table to receive work-sheets from the platen, a device associated with the first- 80 mentioned paper-table to hold a work-sheet 85 against advance movement, a device associated with the second paper-table to co-operate with a work-sheet of special configuration to prevent further advance thereof after 90 the latter has been advanced to a predetermined extent, and means for concomitantly rendering said devices effective and ineffective.

12. In a typewriting machine, in combination, a revolute platen, means to deliver 95 work-sheets thereto, means to receive work-sheets from said platen, a gripping device associated with said delivery means to hold a work-sheet against advance movement, and a device associated with said receiving means to effect proper positioning of a second work-sheet, said last-mentioned device comprising a spring-pressed pin which may be held in retracted position by said second work-sheet until a perforation therein is 100 advanced to a position to permit entry therein of said pin.

13. In a typewriting machine, in combination, a revolute platen, a rear paper-table, a front paper-table, a presser member 110 to hold a work-sheet against the rear paper-table to prevent advance movement thereof, spring means urging said presser member to effective position, a pin mounted so as to permit projection thereof through a perforation in the front paper-table, spring means yieldingly urging said pin to projected position, and means to retain said presser member and said pin in ineffective positions.

14. In a typewriting machine, in combination, a revolute platen, a rear paper-table, a front paper-table, a presser member to hold a work-sheet against the rear paper-table to prevent advance movement thereof, spring means urging said presser member to effective position, a pin mounted so as to permit projection thereof through a perforation in the front paper-table, spring means yieldingly urging said pin to projected position, and means for concomi- 125 130

- stantly withdrawing said presser member and pin to ineffective positions.
15. In a typewriting machine, in combination, a revolute platen, a rear paper-table to deliver superposed work-sheets with interleaved carbons to the platen, a front paper-table to receive work-sheets from the platen, and means for controlling said work-sheets to effect printing of certain entries close together on a record sheet and spaced at greater intervals on a form sheet, including means associated with the rear paper-table made effective to hold the record sheet, and means associated with the front paper-table made effective to co-operate with said form sheet, but ineffective to prevent advance movement thereof until the form sheet has been advanced to a position to receive another entry thereon.
16. In a typewriting machine, in combination, a revolute platen, a rear paper-table to deliver superposed work-sheets with interleaved carbons to the platen, a front paper-table to receive work-sheets from the platen, means for controlling said work-sheets to effect printing of certain entries close together on a record sheet and spaced at greater intervals on a form sheet, including means associated with the rear paper-table adapted to hold the record sheet, and means associated with the front paper-table adapted to co-operate with said form sheet, but ineffective to prevent advance movement thereof until the form sheet has been advanced to a position to receive another entry thereon, and means to render said holding means and said co-operating means ineffective.
17. In a typewriting machine, in combination, a revolute platen, a rear paper-table to deliver superposed work-sheets with interleaved carbons to the platen, a front paper-table to receive work-sheets from the platen, means for controlling said work-sheets to effect printing of certain entries close together on a record sheet and spaced at greater intervals on a form sheet, including means associated with the rear paper-table adapted to hold the record sheet, and means associated with the front paper-table adapted to co-operate with said form sheet, but ineffective to prevent advance movement thereof until the form sheet has been advanced to a position to receive another entry thereon, a handle, and means controlled by said handle for rendering said holding means and said co-operating means ineffective.
18. In a typewriting machine, in combination, a revolute platen, a platen frame comprising end walls and a paper-table to deliver work-sheets to said platen, a presser member adjacent each end wall adapted to co-operate with said paper-table to grip a work-sheet and hold it against advance movement, a pivoted lever for each of said presser members, a spring for each of said levers to swing the same to effect movement of the presser members to effective position, a handle, and means controlled by said handle for actuating said levers and withdrawing both of said presser members concomitantly.
19. In a typewriting machine, in combination, a revolute platen, a platen frame comprising end walls and a paper-table to deliver work-sheets to said platen, a presser member adjacent each end wall adapted to co-operate with said paper-table to grip a work-sheet and hold it against advance movement, a pivoted lever for each of said presser members, a spring for each of said levers to swing the same to effect movement of the presser members to effective position, a handle, means controlled by said handle for actuating said levers and withdrawing both of said presser members concomitantly, and means to hold said handle in position with said presser members in ineffective position.
20. In a typewriting machine, in combination, a platen around which superposed work-sheets and interleaved carbons are fed from the receiving side to the delivery side thereof, and collating means made effective at will whereby one of said sheets will be held at one of said sides of the platen against longitudinal movement, and another sheet will be engaged at the other side of the platen and automatically arrested after movement to a predetermined position.
21. In a typewriting machine, in combination, a revolute platen, means to guide two work-sheets and an interleaved carbon sheet thereto, and sheet-controlling means including means to grip the inner sheet and hold the same against movement and mechanism permitting movement of the outer sheet until it is advanced to a position determined by the configuration of said outer sheet, and then holding the latter against advance movement.
22. In a typewriting machine, in combination, a revolute platen, means to guide two work-sheets and an interleaved carbon sheet thereto, means to grip the inner sheet to hold the same against movement, and means to co-operate with the outer sheet, permitting the latter to be advanced to a position determined by the configuration of said outer sheet and then holding the same.
23. In a typewriting machine, in combination, a revolute platen, means to guide two work-sheets and an interleaved carbon sheet thereto, means to grip the inner sheet and hold the same against movement, means to co-operate with the outer sheet, permitting the latter to be advanced to a position determined by its configuration and then holding the same, and means whereby said grip-

ping means and said co-operating means may be made effective and ineffective concomitantly.

24. In a typewriting machine, in combination, a revolute platen, a rear paper-table to present work-sheets to the platen, a front paper-table to receive work-sheets led upwardly from the delivery side of the platen, a spring-pressed pin supported at the rear 10 of the front paper-table for projection therethrough, a spring-urged presser member at each end of the rear paper-table and adapted to engage the same, a rock-shaft supported behind said front paper-table, 15 means controlled by said rock-shaft whereby said pin may be retracted to the rear of said front paper-table, and connections between said rock-shaft and each of said presser members, whereby the latter may be without 20 drawn to ineffective positions.

25. In a typewriting machine, in combination, a revolute platen, means to present two work-sheets and a carbon sheet placed therebetween to the platen, a paper-table positioned to receive the outer sheet when led upwardly from the delivery side of the platen, said paper-table being spaced from the platen sufficiently to enable the carbon sheet and inner work-sheet to be passed 25 therebetween, fingers beneath which the inner sheet is passed at the rear of said paper-table, and which are used in gaging the leading edge of said inner sheet, a side edge gage adjustably mounted on one of said 30 fingers and projecting downwardly therefrom, and means for gripping said inner work-sheet to hold the same against move- 35

ment to enable the outer sheet to be advanced relatively thereto.

26. In a typewriting machine, in combination, a revolute platen, paper-tables on the delivery and receiving sides respectively of the platen, means for controlling two superposed work-sheets to effect printing of certain entries simultaneously on both sheets 45 but at different intervals, including means associated with one of said paper-tables whereby one of said sheets may be held against movement, means associated with the other paper-table to co-operate with the 50 other sheet to prevent a longitudinal movement thereof, but ineffective until the work-sheet has reached a position to receive another entry, and means for rendering said holding means and said preventing means 55 ineffective.

27. In a typewriting machine, in combination, a revolute platen, means to guide two work-sheets and an interleaved carbon-sheet therearound, means to grip one of said sheets 60 at one side of the platen to hold the same against movement, means to co-operate with the other sheet at the other side of the platen permitting the latter sheet to be shifted longitudinally to a position determined by 65 its configuration, and then holding the same, and means whereby said gripping means and said co-operating means may be made effective and ineffective concomitantly.
